UNITED STATES PATENT OFFICE.

AMSON G. ILLCH, OF NEW YORK, N. Y.

ATTACHMENT-HOOK FOR SAFETY-BELTS.

1,374,738.

Specification of Letters Patent.

Patented Apr. 12, 1921.

Application filed September 11, 1920. Serial No. 409,693.

To all whom it may concern:

Be it known that I, AMSON G. ILLCH, a citizen of the United States, and resident of New York, in the county of New York and 5 State of New York, have invented certain new and useful Improvements in Attachment-Hooks for Safety-Belts, of which the following is a specification.

This invention relates to an improved 10 hook or bolt which is built into a window frame or casing and provides a means to which a window cleaner may attach a safety belt.

The object of this invention is to provide 15 a hook or bolt of the character described which may be readily slipped into position during the course of construction and permanently built into the structure by subsequent structural members.

20 Many so called safety hooks have been devised but have, for the most part, been unsatisfactory on account of insecurity or on account of the expensive nature both to manufacture and install.

25 A further object of this invention is to provide a device of the character described, which is economical in cost of manufacture, practically eliminates the cost of placement on the job and provides the greatest degree 30 of security to the user.

These objects are attained by means of the device described in the specification and illustrated in the accompanying drawings, in which;

35 Figure 1 is a perspective view of the device.

Fig. 2 is a sectional plan view through a window casing or jamb showing the device attached.

40 Fig. 3 is an elevation of a portion of the window frame and jamb showing the device attached, and in which a portion is broken away for better illustration.

Figs. 4 and 5 show modified forms which 45 will be hereinafter fully described.

Referring in detail to the parts, 11, designates the projecting neck portion of the device and is formed with a knob or safety-belt attachment-head, 12. The neck portion 50 extends integrally from the base portion, 13, and has an inwardly bent and prolonged end, 14, and a contacting surface 15. This contacting surface, together with surface 16, formed upon the neck, engages the 55 inner and outer surface of the staff molding, 17, of the window casing, 18. The

staff molding, 17, is provided with a suitable perforation, 19, through which the end, 14, is passed. A seat or locking lug, 20, is formed by the prolongation of the base, 13, 60 and is stiffened or reinforced by the web 21.

The device is made of any suitable metal and in practice, slipped into position by the mechanic just prior to the introduction of the structural member, 22, which may be of 65 masonry or any other structural material and acts by its contact with the lug or seat, 20, to permanently lock the hook in position.

In Fig. 4, a Z-shaped base member, 23, is provided which has formed thereon, an 70 L shaped lug, 24, which lug is adapted to engage through the perforation, 23, in the staff molding. The structural member 22, in this case, operates to lock the hook in position, by its contact with the Z base 75 clearly shown.

In the modification shown in Fig. 5, the seat or locking lug 20 is extended and turned, as at 21, to embrace the side of the casing.

80 The construction shown in the drawings, illustrates the application of the device to a metal window and shows the locking unit as masonry. It is obvious however, that with slight modifications, within the scope 85 of the invention, this device may be adopted for use with materials other than shown.

Various modifications may therefore be embodied without departing from the spirit 90 of the invention and it is therefore intended that this invention be not limited to the particular embodiment shown.

What is claimed:

1. In an attachment-hook for safety-belts and window-frames, a window-casing having a perforated staff-molding thereon, means upon the hook for attaching same to and through the staff-molding of the window frame.

2. In an attachment-hook for safety-belts 100 and window-frames, a window-casing having a perforated staff-molding thereon, means upon the hook for attaching same to and through the staff-molding of the window-frame, at a predetermined distance 105 above the lower end thereof.

3. The combination with a window-frame, and staff-molding thereof having a perforation therein, of an attachment - hook for safety - belts, a contacting surface formed 110 upon the said hook engaging with and conforming to the surface of the staff-molding,

and a tongue formation upon the hook, engaging through the perforation upon the staff-molding to hold the hook in position.

4. In a structural member, a window casing, a staff-molding formed therewith and having a perforation therein, an attachment-hook for safety-belts attached to the staff-molding, and means formed upon the hook adapted to engage through the perforation in the staff-molding for attaching same thereto; the said perforation in the staff-molding being adapted to determine the point of attachment.
5. In combination with a window cas-

ing and structural member, an attachment- 15 hook for safety-belts, a staff-molding formed upon the window-casing and having a perforation at a fixed elevation in the side thereof, means formed upon the hook to engage through the perforation on the 20 staff-molding, and a structural member adapted to engage behind the hook to prevent dislodgment.

Signed at New York, in the county of New York, and State of New York, this 25 18th day of June, A. D. 1920.

AMSON G. ILLCH.
